(57) **CLAIM**

The ornamental design for a light bulb, as shown and described.

DESCRIPTION

FIG. 1 is an isometric view of a light bulb.

FIG. 2 is a front view of the light bulb of FIG. 1.

FIG. 3 is a back view of the light bulb of FIG. 1.

FIG. 4 is a left view of the light bulb of FIG. 1.

FIG. 5 is a right view of the light bulb of FIG. 1.

FIG. 6 is a top view of the light bulb of FIG. 1; and,

FIG. 7 is a bottom view of the light bulb of FIG. 1.

The broken-line disclosure represents portions of the light bulb which form no part of the claimed design.
